CARBURETOR

Armand C. Pothier, Woonsocket, R. I.

Application March 20, 1946, Serial No. 655,836

3 Claims. (Cl. 261—44)

1

This invention relates to a carburetor for an internal combustion engine.

One of the objects of this invention is to provide simultaneous controls for the air conduit and the fuel conduit which may be operated so that the desired mixture of air and fuel may be maintained in a desired proportion.

Another object of this invention is to provide conduits which cause the fluid passing through them to mix together with a valve in the air conduit and a valve in the fuel conduit and to simultaneously control the movement of these valves toward and from open and closed position.

Another object of this invention is to concentrically arrange the fuel and air control valves so that both may be operated simultaneously by a rotary motion.

A more specific object of the invention is to provide a relative adjustment between the fuel and air-control valves so that even though these may be operable simultaneously, the range through which one operates with reference to the other may be varied.

With these and other objects in view, the invention consists of certain novel features of construction, as will be more fully described and particularly pointed out in the appended claims.

In the accompanying drawings:

Fig. 1 is an elevation illustrating the carburetor with its reservoir of fuel;

Fig. 2 is a top plan view of the structure shown in Fig. 1;

Fig. 3 is a section on substantially line 3—3 of Fig. 1, illustrating the air control valve in one position;

Fig. 4 is a fragmental detail of the showing in Fig. 3 with the air control valve shown in closed position;

Fig. 5 is a sectional view on substantially line 5—5 of Fig. 2;

Fig. 6 is a section on line 6—6 of Fig. 5;

Fig. 7 is an elevation of the air control valve shown by itself.

In proceeding with this invention, I construct a fuel supply conduit to extend across the longitudinal extent of an air supply conduit with an opening in the fuel supply conduit at substantially the axial line of the air conduit. A needle valve is utilized to control the amount of passage permitted for fuel through this opening and threaded means are provided for axially moving this needle valve. In order to control the air conduit, I have provided a valve which is concentrically arranged with and has bearing upon the fuel conduit and is provided with a bore sub-

2

stantially the size of the inner diameter of the air conduit, this valve being so arranged that it may be rotated to axially align this bore with the axis of the conduit or to be rotated across this conduit to shut off the supply of air. I have arranged that these valves are so connected that the rotary motion of one is transmitted to the other so that both valves are actuated toward and from closed position simultaneously, and I have provided a stop with limiting arms so that the valves will swing through a certain arc to control the proper opening or closing of the valves. The arrangement is also such that the needle valve may be adjusted independently of the air-control valve so that the relative opening and closing operation may be through different ranges.

With reference to the drawings, 10 designates a fuel reservoir which in this instance is designed to carry gasoline or some vaporous fuel to be mixed with air that the proper combustion may be had. A cap 11 is removably positioned upon this reservoir by set screw 12. This cap threadingly receives a fuel supply conduit 14 which extends by means of coupling 15 and pipe 16 downwardly to the lower portion of the reservoir. This conduit is threaded into a boss 17 on the cover 11 and held in position therein by check nut 18. This conduit also threadingly extends into a boss 19 on an air supply conduit 20 having a bore 21 through which air passes. A nut 22 serves as a check nut for holding the threaded conduit 14 in the boss 19 of the air conduit.

Opposite the boss 19 there is also provided another boss 23 and a cylindrical bore 24 extends through the boss 23 and into the boss 19 providing a cylindrical opening for a valve 25 which has a central bore 26 to have bearing upon the fuel conduit 14 and to be rotatable about the same concentrically therewith. This valve 25 is provided with a bore 27 which is of a size substantially the size of the inner diameter 21 of the air conduit 20 and this valve 25 may be rotated from the open position shown in Fig. 3 to the closed position shown in Fig. 4. Its bore 27 will be aligned with the air conduit 21 when in the open position shown in Fig. 3 while its bore 27 will be substantially across or laterally of the conduit 21 when in the position shown in Fig. 4. This valve has the bore 27 spread out somewhat from a true circle by means of a reamer which has been passed through the bore at an angle of substantially 15 degrees to the axis of the bore so as to provide enlarged portions 28 and 29 at the opposite edges of the bore, as shown in Fig. 4,

so that when the valve is in the idling position shown in Fig. 4, there still will be an opportunity for air to pass through the valve, serving as the equivalent of an idling jet.

The valve 25 is provided with a collar 30 which surrounds the fuel conduit 14 and upon which collar there is mounted a sleeve 31 which is fixed thereto by means of a set screw 32 extending through the sleeve and engaging the collar 30. Thus as this sleeve is rotated the valve 25 will also be rotated with it. The sleeve 31 is rotated by means of an arm 33 which is fixed thereto and extends radially outwardly therefrom and is provided with an opening 34 in which a rod is located for movement of the arm 33 from the full line position shown in Fig. 2 to the dotted line position shown in this figure. A hold down screw 35 for cover 35' protrudes upwardly and may be either an enlarged solid head or a spacer under a normal head and an abutment arm 36 is provided on the sleeve to engage one side of this screw 35 to act as a stop and limit the rotary movement of the sleeve in a counterclockwise direction as viewed in Fig. 2 while another arm 37 extends from this sleeve and is provided with a screw 38 which may have its end adjusted and held in adjusted position by a nut 39 to engage the other side of the screw 35 and thus limit the rotary movement of the sleeve in the other direction. Thus I may arrange that the extremes of the position of the bore 27 will be either that shown in Fig. 3 or that shown in Fig. 4.

An opening 40 is provided in the fuel conduit 14 so that as air rushes across this opening an aspirator action is provided, drawing fuel up through the fuel conduit and causing it to mix with the air which passes through the conduit 21. In order that the opening 40 may be more or less free, I have provided a needle valve 41 having a pointed end 42 which extends across the opening 40 and as I draw the conical end 42 further up the inner portion of the conduit 14, a greater opening is provided, whereas if this needle valve moves downwardly, the opening becomes more closed. This needle valve 41 has a threaded portion 43 to engage the upper threaded interior of the conduit 14 while at its upper end this valve is provided with a head 44 in which there is fixed a collar 45 which has a series of radial splits 46 therein to provide resilient portions 47 (see Fig. 6) which will expand into sufficiently firm frictional engagement with the bore 48 of the sleeve 31. The frictional fit of these parts will be such that rotation of the sleeve will also impart rotary motion to the needle valve 41 and thus cause it to move axially longitudinally of the conduit 14 to open or close the opening 40 as the

air control valve is moved from open to closed position. If I wish to have the range of movement varied from one extent to another along the conical portion 42, it is merely necessary for me to engage the head 44 and rotate this needle valve with reference to the sleeve by applying sufficient torsion to overcome the friction in order to accomplish this result.

By the above arrangement, it will appear that 10 the two valves are operated simultaneously and through relative adjustment of these valves the particular range of movement over which the valves operate may be adjusted.

I claim:

15 1. A carburetor comprising an air conduit, a fuel conduit extending across the axis of said air conduit at substantially right angles thereto and of a size substantially smaller than the air conduit to permit the passage of air around the fuel conduit from both sides, said fuel conduit having a radial opening into said air conduit at a location in said fuel conduit no greater than ninety degrees from the direction of the leaving air stream when taken in a plane at right angles to 20 the axis of the fuel conduit and a valve comprising a pin threadedly engaging and extending axially of the fuel conduit and of the same diameter as the conduit and having a conical end to extend across said opening an air valve concentric with said pin to control the flow through the air conduit, means to rotate said air valve and means including a split collar frictionally connecting said pin and air valve to rotate the pin in its threaded opening simultaneously with the rotation of the air valve and thereby axially adjust said conical end across said radial opening.

25 2. A carburetor as in claim 1 wherein said opening is also midway of the air stream in the direction of the axis of the fuel conduit.

30 3. A carburetor as in claim 1 wherein said fuel conduit has a cylindrical outer surface.
